CABINET DOOR FIXTURE

Adolph Marchand, Jackson Heights, N. Y.

Application September 26, 1944, Serial No. 555,804

6 Claims. (Cl. 16—138)

This invention relates to fixtures, particularly hinge fixtures, for doors of cabinets, such as medicine chests and the like. One object of invention is to provide a door fixture for cabinets, chests and the like which will combine three functions. First, the improved fixture serves as a hinge by which the door is supported on the cabinet; second, the improved fixture serves as a stop to limit the extent of door opening to substantially 90° with the door opened to a position substantially normal to the cabinet; third, the improved fixture serves as an impositive catch to hold the door in closed position.

In the common construction of cabinets, such as medicine chests, the door is mounted on the cabinet by either a long hinge or a plurality of hinges spaced along the vertical side of the door and cabinet; in either case such hinges present an unsightly appearance as portions thereof are exposed both at the outside face of the closed door and at the inner face when open. A further object of invention is to provide a hinge fixture, or rather a pair of such improved fixtures for cabinet doors, which will not be visible from the outside of the closed cabinet and which will be semi-concealed and partly visible from the inside of the open cabinet. As contrasted with the usual hinges, the improved hinge fixture is relatively small. An allied object is to provide a hinge fixture in which the hinge or pivot itself is not exposed but is protected and hidden within a casing countersunk in the cabinet door.

In the common construction of cabinets and chests, the door is prevented from opening beyond a position substantially normal to the cabinet by a long limit bar which is pivoted at one end to the door and is provided at the other end received within the cabinet with an elongated slot in which is slidably received a pin secured on the cabinet. This type of limit stop is unsightly because of the long limit bar and its exposed connections to door and cabinet. Moreover, but a single one of this type of limit stop can be used, namely, near the top of the door, because a limit bar of this character if added near the bottom of the door would greatly interfere with the usable space of the bottom shelf of the cabinet. Lastly, this common type of limit stop is not satisfactory from the standpoint of performance, as it cannot be made sufficiently strong, especially at its articulated ends. A further object of invention is to combine a limit stop with the improved hinge fixture, which shall be of much smaller dimensions than the usual limit bar and which will be considerably stronger and more satisfactory in performance.

By consolidating the limit stop as part of the hinge fixture, there will be available two such limit stops, one at the top fixture and one at the bottom fixture.

5 In the common construction of cabinets, a catch or latch is provided, as a separate unit, to hold the door impositively in closed position. Such latches as commonly employed comprise two coacting parts, one of them secured to the door close to its distal edge and the other secured to the cabinet itself. Such latch parts, attached as they are to the door, mar its appearance and they likewise mar the appearance of the cabinet, at least the side of the cabinet frame opposite its hinged side. A further object of invention is to combine an impositive catch with the improved door fixture, so that the door will not be marred, both on its outside face and at the distal edge of its inside face, with separate latch parts. By thus combining the catch with the hinge fixture, these surfaces and parts of the door will be entirely free of any mechanical members. Moreover, there will be possible the provision of an impositive catch at both the upper and lower fixtures.

10 For the attainment of the foregoing and such other objects of inventions as may appear or be pointed out above, I have shown an embodiment of my invention in the accompanying drawing, 15 wherein—

20 Figure 1 is a perspective view of a cabinet having the improved door fixtures, with the door open;

25 Figure 2 is a plan view of the improved fixture in open position;

30 Figure 3 is a sectional plan view of the fixture in closed position;

35 Figure 4 is an elevational section taken on the line 4—4 in Figure 2;

40 Figure 5 is an elevational view of the fixture housing as seen on the line 5—5 of Figure 2;

45 Figure 6 is an enlarged section taken on line 6—6 of Figure 5, and also shows the lug projection which coacts with the spring catch; and

50 Figure 7 is an enlarged perspective view of the articulation between the pair of limit bars, the parts being separated to show their construction.

The improved door fixture is shown in connection with a medicine chest designated generally 1 having a border frame constituted of top, bottom, left and right sides, respectively 2, 3, 4 and 5. The body of the medicine chest is set into the wall with its border frame exposed in flush relationship to the wall. At the right side of the chest is hingedly supported a door 6 which is fabricated, like the chest itself, of metal plate and has flanges

1 at each side, the edges of which provide the back rest for a mirror (not shown). The door is also provided near its distal edge with a top and bottom rubber cushion 8 which abuts against the cabinet frame when the door is closed. A top and a bottom door fixture of this invention is provided to hinge the door to the right side of the chest. The improved fixture will be described with reference to the lower fixture; the upper fixture is quite similar except for certain features which will be later noted.

The improved fixture comprises an angle member 10 which is fixed to the lower side 3 of the border frame near the right edge of the frame and close to the bottom edge of frame side 3, and a casing 20 which is embedded in and secured to the door 6. Conveniently, the angle member 10 is secured to the border frame by machine screws or bolts, or it may be riveted or welded thereon. Member 10 has been termed an "angle" member because for a greater part of its length except at its both ends, it is in the form of an angle presenting a horizontal disposed ledge 11. Casing 20 is positioned near the proximal edge of the door and close to its bottom edge, in a location opposite that of angle member 10. The depth of casing 20, i. e., the extent to which it is embedded in door 6 is less than the dimension of the door flanges 7, Figure 1, so that the casing will not contact the back of the mirror which is placed against the door, as described above. The end of the casing near the proximal edge of the door, designated 21 in Figures 1 and 2, touches the inside face of the flange 7 along the proximal edge of the door; the casing may be held securely in the opening cut out in the door for it by means of a bolt, screw or rivet passed through door flange 7 and end 21 of the casing. In addition, a second point of securing of the casing to the door will be subsequently described.

The right end of ledge 11 of angle member 10 extends to the right in the form of a neck piece 12 having a rounded head 13 which is pivoted to the bottom wall 22 of the casing at 14; preferably pivot 14 is a riveted articulation permitting the casing 20 (and of course the door) to turn from open position, Figure 2, to closed position, Figure 3. The head 13 is rounded so as to require less clearance within which to turn; the casing 20 may be made sufficiently deep to enable rounded head 13 to clear the rear wall 23 of the casing or it may be made of reduced depth, as shown, and a local bulge 24 provided in rear wall 23 to afford clearance for rounded head 13.

Ledge 11 of angle member 10 stops short of the left end of the member, and the left end is bent 90° to form a flange 15, the end of which is shaped as a pointed head 16, most clearly shown in Figure 6, of reduced width and connected to flange 15 by a reduced neck 17 to form a notch 18 on each side of neck 17. Near the distal end of casing 20, i. e., at its end opposite pivot 14, and in a position to be contacted by pointed head 16 is provided a spring 25 made of flat spring metal bent in U-shape and secured to rear wall 23 of the casing by a rivet, bolt or screw 26 passed through the web portion of the U-shaped spring. The ends of the two legs of spring 25 are rounded and turned inwardly to present rounded lips 27. As clearly shown in Figure 6 the space between rounded lips 27 is somewhat less than the greatest width of pointed head 16 but sufficient to allow entry of the pointed end of the head 16. In the closing position of the door, pointed head 16 enters between the lips 27 spreading the legs of

spring 25 apart until the widest part of the head has passed therebetween, whereat the rounded lips spring behind the head to be received in notches 18 and to impositively hold the door in closed position.

The means for limiting door opening to substantially 90°, i. e., with the door substantially normal to the cabinet, comprises a pair of limit bars 31 and 32, bar 31 being pivoted at one end to ledge 11 of angle member 10 at 33 while bar 32 is pivoted to the top wall 28 of casing 20 at 34; pivot connections 33 and 34 may be rivets, bolts, screws or other form of articulation. The distal ends of limit bars 31 and 32 are articulated together with the aid of a third member 35 which is placed between the distal end portions of bars 31 and 32. Connecting member 35 has a pair of depending flanges 36 which abut the side edges of the underlying bar 31, member 35 being frictionally held between its flanges 36 at the end of bar 31. All three members 31, 35 and 36 are provided with apertures, respectively, 31a, 35a and 36a, which are brought into vertical alignment, and the three members articulated together by a rivet or bolt 37, see Figure 2. Connecting member 35 is further provided with an upstanding lug 38 which is so positioned relative to aperture 35a, i. e., to pivot 37, Figure 2, that when the door is in its extreme open position, normal to the cabinet, as in Figure 2, the right edge 39 of bar 32 abuts against lug 38 to prevent further turning between the two limit bars.

The improved fixture, which has been described with reference to the fixture at the lower edge 35 of the cabinet and door shown in Figure 1, may be also used without change for the fixture at the upper edge of the cabinet and door. However, the upper fixture in Figure 1 has been slightly modified in Figure 1 for the purpose of improving appearance. Whereas the ledge 11 of the angle member 10 of the lower fixture is at the lower edge of member 10 with limit bar 31 in overlying relation to the ledge 11, the ledge 11' of angle member 10' of the upper fixture is at the top edge of member 10 with limit bar 31' in underlying relation to ledge 11'.

In addition to the securing of the proximal end of casing 20 within the door, as by a bolt, screw or rivet passed through that end of casing 20 and flange 7 of the door, as described above, the casing 20 may be further secured to the door near its distal end, as by a screw, bolt or rivet passed through the lower wall 22 of the casing and flange 7 of the door. Although the angle member 10 is shown secured to the cabinet and the casing so embedded in the door, it is apparent that the member 10 may be secured to the door and the casing 20 embedded in the cabinet, for example, in lower border 3. It should be observed, best from Fig. 3, that in the closed position of the door, the limit bars 31 and 32 are entirely received in folded condition within casing 20, and that the ledge 11 of angle member 10 is also received within casing 20.

I claim:

1. A door fixture for a cabinet having a flush border and a door hingedly and vertically mounted at one side thereof, in combination, an angle member secured to the cabinet border close to the said hinge side of the cabinet and having an outwardly projecting horizontal ledge and an outwardly projecting vertical flange at its end distal to the said hinge side of the cabinet, the said horizontal ledge having a portion extending from the end of the angle member proximal to

the said hinge side of the cabinet and terminating in a rounded head, the said vertical flange terminating in a pointed head connected to the flange by a reduced neck to present notches on opposite sides of the said neck, a casing embedded in the said door close to the said hinge side thereof and opposite to the said angle member, the said rounded head extension of the ledge of the angle member being received within the said casing near its end proximal to the said hinge side of the cabinet and pivoted to the bottom thereof, a flat spring bent U-shape and secured at its web to the rear wall of the casing near its end distal to the said hinge side of the cabinet, the ends of the two legs of the said U-shaped spring being turned inwardly to form rounded lips, the said pointed head of the angle member being yieldingly received between the said rounded lips of the spring in the closed position of the door with the said rounded lips spring-pressed in the said notches, a bar pivoted at one end to the said horizontal ledge of the angle member near its distal end, a second bar pivoted at one end to the top wall of the said casing, and a member for pivotally connecting the distal ends of the said two bars, said connecting member being disposed in overlying relation to the first said bar and having a pair of depending flanges adapted to frictionally grip the said distal end portion of the said bar, said member being disposed in underlying relation to the second said bar and having a projecting lug adapted to be contacted by the side edge of the said bar near its said distal end to limit the relative turning of the said two bars in the position of the door substantially normal to the cabinet, the said pair of limit bars being adapted upon closing the door to be received in folded relation and together with the said horizontal ledge of the angle member within the said casing.

2. A door fixture for a cabinet having a flush border and a door hingedly and vertically mounted at one side thereof, in combination, an angle member secured to the cabinet border close to the said hinge side of the cabinet and having an outwardly projecting horizontal ledge and an outwardly projecting vertical flange at its end distal to the said hinge side of the cabinet, the said horizontal ledge having a portion extending from the end of the angle member proximal to the said hinge side of the cabinet and terminating in a rounded head, the said vertical flange terminating in a pointed head connected to the flange by a reduced neck to present notches on opposite sides of the said neck, a casing embedded in the said door close to the said hinge side thereof and opposite to the said angle member, the said rounded head extension of the said ledge of the angle member being received within the said casing near its end proximal to the said hinge side of the cabinet and pivoted to a side wall thereof, a flat spring bent U-shape and secured at its web to the rear wall of the casing near its end distal to the said hinge side of the cabinet, the ends of the two legs of the said U-shaped spring being turned inwardly to form rounded lips, the said pointed head of the angle member being yieldingly received between the said rounded lips of the spring in the closed position of the door with the said rounded lips spring-pressed in the said notches, a bar pivoted at one end to the said horizontal ledge of the angle member near its distal end, and a second bar pivoted at one end to a side wall of the said casing, and a member for pivotally connecting the distal ends of the said

two bars, said connecting member having a pair of flanges adapted to frictionally grip the said distal end portion of one of the said bars and a projecting lug adapted to be contacted by the side edge of the other bar near its said distal end to limit the relative turning of the said two bars in the position of the door substantially normal to the cabinet, the said pair of limit bars being adapted upon closing the door to be received in folded relation and together with the said horizontal ledge of the angle member within the said casing.

3. A door fixture for a cabinet having a flush border and a door hingedly and vertically mounted at one side thereof, in combination, an angle member secured to the cabinet border close to the said hinge side of the cabinet and having an outwardly projecting horizontal ledge and an outwardly projecting vertical flange at its end distal to the said hinge side of the cabinet, the said horizontal ledge having a portion extending from the end of the angle member proximal to the said hinge side of the cabinet and terminating in a rounded head, the said vertical flange terminating in a pointed head connected to the flange by a reduced neck to present notches on opposite sides of the said neck, a casing embedded in the said door close to the said hinge side thereof and opposite to the said angle member, the said rounded head extension of the said ledge of the angle member being received within the said casing near its end proximal to the said hinge side of the cabinet and pivoted to a side wall thereof, a flat spring bent U-shape and secured at its web to the rear wall of the casing near its end distal to the said hinge side of the cabinet, the ends of the two legs of the said U-shaped spring being turned inwardly to form rounded lips, the said pointed head of the angle member yieldingly received between the said rounded lips of the spring in the closed position of the door with the said rounded lips spring-pressed in the said notches, a bar pivoted at one end to the said horizontal ledge of the angle member near its distal end, and a second bar pivoted at one end to a side wall of the said casing, said two bars being articulated at their distal ends and one of the two bars having a projecting lug adapted to be contacted by the side edge of the other bar near its said distal end to limit the relative turning of the said two bars in the position of the door substantially normal to the cabinet, the said pair of limit bars being adapted upon closing the door to be received in folded relation and together with the said horizontal ledge of the angle member within the said casing.

4. A door fixture for a cabinet having a flush border and a door hingedly and vertically mounted at one side thereof, in combination, an angle member secured to the cabinet border close to the said hinge side of the cabinet and having an outwardly projecting horizontal ledge, the said horizontal ledge having a portion extending from the end of the angle member proximal to the said hinge side of the cabinet and terminating in a rounded head, a casing embedded in the said door close to the said hinge side thereof and opposite to the said angle member, the said rounded head extension of the said ledge of the angle member being received within the said casing near its end proximal to the said hinge side of the cabinet and pivoted to a side wall thereof, a bar pivoted at one end to the said horizontal ledge of the angle member near its distal end, and a second bar pivoted at one end to a side wall of the said

casing, said two bars being articulated at their distal ends and one of the two bars having a projecting lug adapted to be contacted by the side edge of the other bar near its said distal end to limit the relative turning of the said two bars in the position of the door substantially normal to the cabinet, the said pair of limit bars being adapted upon closing the door to be received in folded relation and together with the said horizontal ledge of the angle member within the said casing.

5. A door fixture for a cabinet having a flush border and a door hingedly and vertically mounted at one side thereof, in combination, an angle member secured to the cabinet border close to the said hinge side of the cabinet and having an outwardly projecting horizontal ledge and an outwardly projecting vertical flange at its end distal to the said hinge side of the cabinet, the said horizontal ledge having a portion extending from the end of the angle member proximal to the said hinge side of the cabinet, the said vertical flange terminating in a pointed head connected to the flange by a reduced neck to present notches on opposite sides of the said neck, a casing embedded in the said door close to the said hinge side thereof and opposite to the said angle member, the said extension of the ledge of the angle member being received within the said casing near its end proximal to the said hinge side of the cabinet and pivoted to a side wall thereof, and a flat spring bent U-shape, and secured at its web to the rear wall of the casing near its end distal to the said hinge side of the cabinet, the ends of the two legs of the said U-shaped spring

10 being turned inwardly to form rounded lips, the said pointed head of the angle member yieldingly received between the said rounded lips of the spring in the closed position of the door with the said rounded lips spring-pressed in the said notches, the said horizontal ledge of the angle member being adapted upon closing the door to be received within the said casing.

15 6. A door fixture for a cabinet having a door hingedly and vertically mounted at one side thereof, in combination, a member secured to the cabinet close to its said hinge side and having a portion extending from its end proximal to the said hinge side of the cabinet and a latch projection at its end distal thereto, a casing embedded in the said door close to the said hinge side thereof and opposite to the said member, the said extension of the member being received within the said casing near its end proximal to the said hinge side of the cabinet and pivoted to a side wall thereof, spring means near the end of the casing distal to the said hinge side of the cabinet adapted to yieldingly hold the said latch projection in the closed position of the door, a bar pivoted at one 20 end to the said member near its distal end, a second bar pivoted at one end to the said casing near its distal end, said two bars being articulated at their distal ends and provided with means for limiting the relative turning of the said two bars in the position of the door substantially normal to the cabinet, the said pair of limit bars being adapted upon closing the door to be received in folded relation within the said casing.

ADOLPH MARCHAND.
